UNITED STATES PATENT OFFICE.

EMILY A. EKSTRÖMER, OF CHICAGO, ILLINOIS.

DESIGN FOR A BOOK-MARK.

SPECIFICATION forming part of Design No. 37,484, dated July 11, 1905.

Application filed February 18, 1905. Serial No. 246,359. Term of patent 14 years.

To all whom it may concern:

Be it known that I, EMILY A. EKSTRÖMER, a citizen of the United States, residing at Chicago, Cook county, State of Illinois, have invented a new, original, and ornamental Design for a Book-Mark, a facsimile of which is shown in the accompanying drawing.

The figure of the drawing is a plan view showing the design of the book-mark.

I claim—
The ornamental design for a book-mark as shown.

EMILY A. EKSTRÖMER.

In presence of—

CHAS. S. BURTON,
FRED. G. FISCHER.
